(57) **CLAIM**

The ornamental design for a pair of tweezers, as shown and described.

DESCRIPTION

FIG. 1 front, right, and top perspective view of a pair of tweezers, showing my new design.

FIG. 2 is an exploded front, right and top perspective view thereof;

FIG. 3 is a front, right, and top perspective view of a body of the pair of tweezers in FIG. 2;

FIG. 4 is a rear, left, and bottom elevation view of FIG. 3;

FIG. 5 is a front elevation view of FIG. 3;

FIG. 6 is a rear view of FIG. 3;

FIG. 7 is a left side elevation view of FIG. 3;

FIG. 8 is a right side elevation view of FIG. 3;

FIG. 9 is a top plan view of FIG. 3;

FIG. 10 is a bottom plan view of FIG. 3;

FIG. 11 is an enlarged view of an encircled area labeled "11" in FIG. 3; and,

FIG. 12 is an enlarged view of an encircled area labeled "12" in FIG. 3.

The broken lines shown in the drawings are included for the purpose of illustrating portions of the pair of tweezers that form no part of the claimed design.

Dot-dash broken lines in FIGS. 3, 11, and 12, framing portions of the claimed design that are illustrated for enlargements form no part of the claimed design.

1 Claim, 12 Drawing Sheets
